CATAPULT

Lytle S. Adams, Irwin, Pa., assignor to All
American Aviation, Inc., a corporation of
Delaware

Application November 12, 1938, Serial No. 240,201

11 Claims. (Cl. 124—17)

This invention relates to mechanical devices for projecting articles through the air, particularly in the aviation industry and in warfare, although the invention is not restricted to such uses.

The device depends for its motive force upon energy stored in rubber cords such as are used in the aviation industry for taking up the shock upon the airplane from the wheels in taking off and making landings, and one of the objects of my invention is to enable a number of such cords to be combined as desired for obtaining the amount of energy required for projecting different articles and for a variety of purposes.

Other objects of the invention are to provide for safeguarding the apparatus from the violence of its action under full power, and to enable it to be tripped automatically and reset manually by a single attendant, as hereinafter described.

The invention may be readily embodied in portable forms adapted to throwing grenades and bombs, launching depth charges, projecting torpedoes, and similar purposes, and for accelerating articles to be picked up by moving vehicles. In the accompanying drawings the invention is illustrated as applied to catapulting mail and express pouches for enabling them to be caught and carried away by aircraft flying overhead.

Referring to the drawings,

Fig. 1 is a side elevation of a catapult as arranged for projecting a pouch to be picked up by an airplane, a portion of the cover being removed to expose the working parts within;

Fig. 2 is a plan view of the same with the entire cover removed;

Fig. 3 is an end elevation looking at the discharge end of the apparatus shown in Figs. 1 and 2;

Fig. 4 is a plan of the head, trigger and snubbing mechanism, drawn to an enlarged scale;

Figs. 5 and 6 are side views of the trigger portion of the same, Fig. 5 being a section on the line 5—5 in Fig. 4, looking in the direction of the arrows, and Fig. 6 looking in the opposite direction;

Fig. 7 is a face view of the head; and

Fig. 8 is a perspective view of the complete catapult.

The catapult shown in the drawings comprises a cornucopia shape frame made of angle and channel irons and covered on the sides and top with sheet metal 11, the rear portion of the frame being normally closed by means of a hinged cover 12 fitted with a clasp 13 similar to those used for

automobile hoods so as to permit it to be raised upon its hinged end 14 to give access to the working parts of the apparatus.

The side frame members 15 converge at their rear ends and are secured to angle connections 16 provided with alining bearings for a cross shaft 17, the ends of which are fixed in lugs 18 formed to slide on the guides 19 which in turn are supported in brackets 20 bolted to planks 21 or other secure foundation. Springs 22 are arranged on the guides 19 between the brackets and lugs 18 to take up some of the shock on the frame when the catapult is discharged.

The front ends of the frame members 15 are adjustably supported on movable posts 23 by means of swivels 24 which can be clamped to the posts by hand screws 25 at any desired vertical position. The lower ends of the post 23 are hinged to the planks 21 or other foundation support so as to be free to oscillate lengthwise of the catapult to permit the entire frame and mechanism supported thereby to move back and forth, the two planks or side supports constituting a flexible articulated foundation for the rigid metal frame work which supports the working parts of the apparatus.

In the space between the front and rear ends of the side frame members 15 are cross members 26, 27 for supporting the catapult head 28 and snubbing mechanism, which are normally held in position for operation by means of a tube 29 secured to said cross members in such a way as to be adjustable in a vertical angle but held against longitudinal movement. In the device shown, the rear end of the tube 29 is provided with a thrust member or flange 30 having a rounded face to bear against the vertical flange or leg of the cross member 26 through which it passes, and near the forward end of the tube 29 is a collar 31 which works between the vertical struts 32 connecting the upper and lower cross members 27 to guide the tube in a vertical plane.

Below the forward end of the tube 29 and extending forwardly in front of and below the normal position of the head 28, are a series of finger bars 33, supported at their rear ends on the lower cross member 27 and at an intermediate point by the cross member 34 which is bent at the middle to conform approximately to the arc of a circle having its center at the normal center position of the catapult head, the finger bars being slightly splayed to conform to the flare of the frame. Thus the finger bars 33 form a longitudinal cage-like support for the pouch or article to be projected, as indicated in Fig. 1,

with their front ends entirely free to avoid entangling any moving part of the device during the discharge thereof.

The catapult head 28 is composed of a light metal hub or center 35, adapted to slip loosely over the forward end of the tube 29, and a canvas or vulcanized rubber face plate 36, stiffened by an outer ring 37 and radial ties 38 connecting the rings to a center disc portion 39 of the hub. Preferably the parts of the head are vulcanized together to form a comparatively stiff but flexible ensemble that will withstand severe shocks without breaking or coming apart.

Around the circumference of the face plate 36 inside its outer edge are spaced a series of U bolts 40 riveted through the rear face of the plate and straddling the outer ring 37, with their closed ends projecting through the front face to provide a series of loops into which the rear ends of the rubber cords 41 may be hooked by means of the S-hooks 42 with which the latter are fitted. The forward ends of the cords 41 are provided with similar hooks for engaging in the front cord supports 43, hinged one on each side to the vertical side bars 44 of the frame at its forward end. The hinges between the cord supports and frame side bars permit the supports to swing around their vertical axes from their normal positions facing inwards towards the catapult head prior to discharge to follow the line of flight upon discharge, and may face outwards at the completion thereof.

In the device illustrated there are twenty U-loops 40 and each cord support 43 is provided with ten holes 45 to receive the S-hooks on the front ends of the cords 41, but only ten cords are shown in use. The number of cords may be varied from two or four to twenty, depending upon the force needed for the particular object to be projected, and the size of the cords may be changed also to adapt the device to different loads and distance requirements, these cords being procurable in several sizes and lengths.

The catapult head is secured to the snubbing device by means of a cable 46 which is attached to an eye 47 on the hub 35 (see Fig. 6) and extends through a slot 48 in the lower side of the tube 29 to the rear end thereof, where it is connected to a solid plunger 49, having a loose sliding fit in the tube. A compression spring 50 in the tube 29 presses the plunger 49 towards the rear end of the tube, the front end of the spring seating against a washer 51 which abuts against the inner end of a tubular liner 52 secured in the front end of the tube 29 to strengthen it, as shown in Fig. 4. The rear end of the tube 29 is closed by a diaphragm 53 having an aperture 54 to check the flow of air into and out of the space in the tube between it and the plunger 49, thus acting as a recoil buffer to prevent the plunger from slamming against the diaphragm after each discharge of the catapult. There is sufficient slack in the cable 46 to permit the head 28 to be thrown to about the front end of the frame before checking it, this slack being coiled on the finger bars 33 behind the head in its normal position as shown in Fig. 1.

The trigger mechanism comprises a trigger lever 60 pivoted to lugs or ears 61 on the exterior of the hub 35 near its rear end, and bent to project through a pair of oppositely disposed slots 62 in the sides of the tube 29 forward of the spring abutment 51, so that its extremity may be engaged by a keeper member 63 pivoted to lugs or ears 64 on the hub diametrically opposite the lugs 61.

The keeper is provided with a roller 65 which fits into a slight notch in the face of the trigger latch near its extremity to assist in holding the keeper and trigger in latched position, as shown in Fig. 4, in which position the catapult head is securely held in place on the end of the tube 29.

The keeper may be released by a jerk on the releasing lever 66, which is pivoted to a bracket 67 on the inside of the frame, as shown in Fig. 2, 10 and which is connected to the keeper 63 by means of a removable link 68 when the device is set ready to be tripped to project a bag or other article, as shown in full lines in Fig. 4. Upon pulling the cord 69, the operating end of the 15 lever 66 will move away from the keeper 63 and carry the link 68 along with it, dislodging the roller 65 from its seat, and freeing the trigger 60, which swings out of the tube to release the head 28, as shown in broken lines in Fig. 4. As 20 the head and keeper move away, the pin connection 70 pulls out of the jaws 71 on the end of the keeper, leaving the link 68 pinned to the releasing lever 66.

During the setting of the head, while stretching 25 the rubber cords and placing the article to be projected in operative position, the link 68 is swung around on its pin connection 70 to project into the adjacent slot in the tube 29, as shown in dot and dash lines in Fig. 4, where it is pinned 30 in place by thrusting the removable pin 72 through the hole 73 into engagement with the hole in the end of the link; and when everything is ready for the catapult to be actuated to project the article, the pin 72 is removed from the hole 35 73, the link is swung into position to connect with the end of the releasing lever 66, and the pin 72 is replaced to connect the link and lever 40 as shown in full lines in Fig. 4. Thus during the setting of the device the releasing lever is out of operative connection with the keeper, and the trigger is positively locked in position to hold the catapult head against movement.

If the load to be projected does not weigh more 45 than one man can lift, a single attendant can place the load in the catapult, draw back the energy storing cords one at a time and hook them in place on the face of the head or on the cord supports 43, set the trigger mechanism, and the apparatus is ready for action.

In the form of apparatus illustrated, which is 50 shown as arranged for accelerating a pouch to be picked up in the air by a passing aircraft, the lifting cable or line 75 attached to the pouch is provided at its other end with a loop or other 55 means for engagement with a trailing cable, grapple, hook or other device carried by the aircraft, and when contact is made therewith, the sudden jerk on the cable 75 is transmitted to the releasing lever 66 by means of a light cord 76 connecting the cable and cord 69, which parts after serving its purpose of actuating the releasing mechanism. The cord 76 may be adjusted to 60 operate the releasing mechanism before all the slack is taken out of the cable 75, so that the bag is started on its forward and upward movement by the catapult before the drag due to its weight and inertia attains a magnitude sufficient to over stress the lifting cable and parts connected to the aircraft.

The invention is not restricted to the details of construction shown nor to the purposes described, as it is susceptible of many modifications to suit the requirements of different kinds and conditions 65 of use.

What I claim as my invention is as follows:

1. A catapult having a rigid frame comprising side members extending from end to end thereof, a base having relatively movable parts underlying said side members, a vertically adjustable mounting for one end of the frame and a pivot for the other end both supported on said base, said adjustable mounting comprising two supporting rods, one on each side of the frame, each hinged to said base at one end and provided with an adjustable clamp for engaging the adjacent frame side member, whereby the angle of inclination of the frame to the horizontal can be readily changed as desired by changing the position of said clamps with respect to said rods irrespective of the position of said base.

2. In a catapult of the kind described in claim 1 wherein the supporting rods are hinged to swing in planes parallel to the longitudinal axis of the device, spring recoil means associated with the pivoted end of the frame, between it and the adjacent parts of said base.

3. A catapult having a frame, a vertically adjustable mounting for one end of the frame, a pivot mounting for the other end of the frame, a disc-like head for engaging an article to be projected, trigger mechanism for releasably holding said head near the pivot end of the frame, and a plurality of rubber cords each independently secured at one end to said head near its perimeter and at the other end to said frame near its vertically adjustable end, whereby the angle of discharge flight of said article to the horizontal and number of cords supplying energy thereto can be adjusted to suit the desired range.

4. A resilient head for a catapult comprising a metal center part, a peripheral ring, metal connections radially disposed between said center part and ring, and vulcanized rubberized fabric embracing said metal parts and ring and having sufficient stiffness to form a support for the article to be projected.

5. A resilient head for a catapult comprising a metal center part, a peripheral ring, metal connections between said center part and ring, and vulcanized rubberized fabric embracing said metal parts and ring and having sufficient stiffness to form a support for the article to be projected, said center part having a hub projecting from its rear side for supporting said head in position to be releasably engaged by a trigger mechanism.

6. A resilient head for a catapult comprising a metal center part having a hub for receiving a supporting and guiding member, a peripheral ring, metal connections between said center part and ring, and vulcanized rubberized fabric embracing said metal parts and ring and having sufficient stiffness to form a support for the article to be projected, said ring supporting a circular series of attaching members projecting from said head to receive the ends of individual energy applying members.

7. A catapult having a frame with an open front end, a guide member connected to the rear end of said frame, said guide member being unrestrained at its front end and free to pivot about its rear end in a vertical plane extending centrally of the frame, a resilient head having a hub adapted to seat on the free end of said guide member, trigger mechanism between said hub and guide member for retaining said head

against movement, energy storing cords connected to said head and to the front end of said frame near its sides, and means for altering the vertical height of the points of connection of the front ends of said cords to the frame.

8. A catapult having a frame with an open front end, a retaining and guide member connected at its rear end to the rear end of said frame and with its front end exposed, a resilient head having a hub adapted to seat on the exposed end of said guide member, trigger mechanism between said hub and guide member for retaining said head against movement, energy storing cords connected to said head and to the front end of said frame near its sides, and means for supporting an article to be projected in front of said head, said article support having fingers projecting between said cords to avoid contact therewith.

9. A catapult having a frame with an open front end, a guide member connected to the rear end of said frame, spring means associated with said guide member and an air check for snubbing the recoil action thereof, a resilient head having a hub adapted to seat on the free end of said guide member, a flexible cable connecting said spring means and head, trigger mechanism between said hub and guide member for retaining said head against movement, energy storing cords connected to said head and to the front end of said frame near its sides, and means for releasing said trigger mechanism to permit said head to be projected by said cords as far as said flexible cable will permit.

10. A catapult having a frame providing a support for a trigger mechanism at one end and a plurality of attaching points for energy storing cords at the other end, a circular head adapted to be restrained by said trigger mechanism, said head being provided with circumferentially spaced means for securing a plurality of energy storing cords thereto, energy storing cords stretched between said attaching points and securing means in spaced non-interfering relation, means below said head for supporting an article to be projected, said article supporting means comprising spaced bars having portions projecting between said energy storing cords out of contact therewith and free from interference therewith during the discharge movement of said head.

11. A catapult having a rigid frame articulated to separate base members providing a flexible foundation structure, said structure comprising in addition to said frame and base members a vertically adjustable mounting for one end of the frame movably supported upon said base members and a pivoted support for the other end of the frame carried by said base members whereby the angle of inclination of the frame to the horizontal can be readily changed as desired, and recoil means for the pivoted end of said frame including a pair of longitudinal slideways mounted one on each of said base members and independent of each other, respectively, slides on said ways, springs between said slides and the ends of said ways, and a pivot member carried by said slides to which said frame is pivotally connected.

LYTLE S. ADAMS.
